ELECTRIC-CONDUIT FITTING.

1,043,797.

Specification of Letters Patent.

Patented Nov. 12, 1912.

Application filed January 27, 1910. Serial No. 540,349.

To all whom it may concern:

Be it known that we, CARL H. BISSELL and CHARLES B. GARLING, of Syracuse, in the county of Onondaga and State of New York, 5 have invented a certain new and useful Electric-Conduit Fitting, of which the following is a specification.

Our invention has for its object the production of a particularly simple and efficient 10 structure including an electric conduit fitting, a globe for an incandescent lamp supported by a socket within the fitting, a guard for the globe, and means for detachably securing the guard to the fitting; and 15 to this end it consists in the combinations and constructions hereinafter set forth and claimed.

In describing our invention, reference is had to the accompanying drawing, in which 20 like characters designate corresponding parts in all the views.

Figure 1 is an elevation of a device embodying our invention. Fig. 2 is an enlarged elevation, partly in section, of parts 25 of said device. Fig. 3 is a section on line A—A, Fig. 1. Fig. 4 is an end view of the guard for the globe. Fig. 5 is a fragmentary view of the guard, and Fig. 6 is a perspective view of the locking member for the 30 guard.

1 is the body of the electric conduit fitting, said body having one or more outwardly extending internally threaded nipples 2 for connection with conduits, not illustrated, 35 which inclose electric wires. The body is usually cylindrical in general outline and formed with a flat bottom 3 and with an axially projecting cylindrical portion 4 open at its end and forming an axial continuation of the portion of the body provided with the nipples 2. Obviously, the body may be provided with any other suitable means instead of the nipples 2 for connecting said body to one or more conduits. The body is also 40 formed with internal integral posts 5 projecting from the bottom 3 thereof toward the open end of the projecting portion 4, these posts 5 being spaced apart and designed to support an electrical appliance, as 45 a lamp and its socket, the latter being secured to the posts 5 by screws turning in openings 6 in the ends thereof, and the projection of said posts above the bottom 3 providing passages for wires between the electrical appliance and said bottom 3. The

projecting portion 4 of the body 1 is provided with an internal threaded surface 7 extending from its outer end and terminating short of the inner end thereof, and is also provided with an internal annular 60 flange or shoulder 8 located beyond the threaded surface 7, and with an external annular shoulder 9, usually formed by reducing the outer end of the projecting portion 4.

10 is an elongated globe having a threaded 65 end which turns in the projecting portion 4 of the body against a packing ring 11 inserted between the end of said globe 10 and the internal annular flange or shoulder 8. By reason of the packing ring, shoulder, and 70 threaded connection, a vapor-tight joint is formed between the body 1 and the globe 10.

A suitable guard for the globe is provided, the same being here shown as comprising a supporting member or ring 12 mounted on 75 or encircling the end of the projecting portion 4 of the body, and abutting against the external annular shoulder 9, and side members 13 depending from the member or ring 12. Preferably, the member or ring 12 is 80 formed with outwardly extending perforated ears 14 of less thickness than the main part of the ring, and the ends of the members 13 extend through and are riveted to the ears 14, Fig. 5. The intermediate portions of the side members 13 are encircled by 85 bands 15 suitably connected thereto.

The supporting member or ring 12 is secured to the projecting portion 4 of the body 1 by means of a locking member 16 carried 90 by the member or ring 12 and having an edge portion 17 thereof movable into a circumferential groove 18 which is formed in the periphery of the reduced end of said portion 4 between the end face thereof and 95 the shoulder 9 and is normally covered by the member or ring 12. Said locking member 16 is here shown as pivoted at 19 at one end between outwardly extending ears 20 on the member or ring 12, the edge portion 100 17 of the pivoted end of the member 16 being movable through a hole 21 which is formed in the contiguous portion of the ring and is normally aligned with the groove 18 and projecting into the groove 18 when the 105 locking member is in its operative position, and another edge portion 22 of said pivoted end being located opposite to but out of the groove 18, when the locking member is in its inoperative position. It is thus apparent 110

that the edge portions 17 and 22 of the locking member 16 are dissimilarly spaced from the axis of the pivot 19 for said member 16. Said locking member is formed arc - shape 5 in order to conform to the curvature of the member or ring 12 when said locking member is in its operative position.

In order that the guard may not be removed and the globe and electric appliance 10 tampered with by unauthorized persons, means is provided for preventing the removal of said guard, and as here shown, the member or ring 12 and the locking member 16 are provided, respectively, with perforated ears 23, 24, the openings or perforations of which are designed to be in alignment when the locking member 16 is in its operative position, Figs. 1 and 3, in order to receive the bail 25 of a padlock 26 shown in 20 dotted lines, Fig. 1.

What we claim is:—

1. The combination of an electrical fitting comprising a hollow body for receiving electric wires, and a projecting portion formed 25 with an external shoulder, the body having means for supporting an electrical appliance, a globe supported by said projecting portion, a guard for the globe including a member coacting with said shoulder, and a locking device carried by the member and engaging said projecting portion below the shoulder, substantially as and for the purpose described.

2. The combination of an electrical fitting 35 comprising a hollow body for receiving electric wires, and a cylindrical portion formed with an external annular shoulder, the body also having means for supporting an electrical appliance, a globe supported by said 40 cylindrical portion, a guard for the globe including a ring encircling the cylindrical portion and coacting with the shoulder and a member pivoted to the ring and engaging the cylindrical portion below said shoulder, 45 substantially as and for the purpose specified.

3. The combination of an electrical fitting comprising a hollow body for receiving electric wires, and a projecting portion formed 50 with a groove in its external face, the body also having means for supporting an electrical appliance, a globe supported by said projecting portion, a guard for the globe including a member mounted on the external 55 face of said projecting portion, and a locking member carried by the first-mentioned member and movable relatively thereto into and out of the groove, substantially as and for the purpose described.

60 4. The combination of an electrical fitting comprising a hollow body for receiving electric wires, and a projecting portion formed with a groove in its external face, the body also having means for supporting 65 an electrical appliance, a globe supported by

said projecting portion, a guard for the globe including a member mounted on the external face of said projecting portion, and a locking member having one end pivoted to the first-mentioned member and provided 70 with edge portions dissimilarly spaced from the axis of the pivot of said end, one of said edge portions projecting into the groove when the locking member is in its operative position and the other of said edge portions 75 being opposed to said groove and located out of the same when the locking member is in its inoperative position, substantially as and for the purpose specified.

5. The combination of an electrical fitting 80 comprising a hollow body for receiving electric wires, and a cylindrical portion formed with a peripheral groove, the body also having means for supporting an electrical appliance within the cylindrical portion, a globe supported by the cylindrical portion, a guard for the globe including a ring encircling the cylindrical portion, and a locking member pivoted to the ring and having one end thereof movable into and out of said groove, the locking member being curved to conform to the curvature of the ring and being close to the ring when in operative position, substantially as and for the purpose set forth.

6. The combination of an electrical fitting comprising a hollow body for receiving electric wires, and a projecting portion formed with a circumferential groove, the body being also formed with means for supporting 100 an electrical appliance, a globe supported by said projecting portion, a guard for the globe including a ring encircling said projecting portion and covering the groove, the ring being formed with an opening extending therethrough and aligned with the groove, and a locking member carried by the ring and having a portion movable into the groove through said opening, substantially as and for the purpose described.

7. The combination of an electrical fitting, comprising a hollow body for receiving electric wires, and a projecting portion formed with an external shoulder and with a groove 115 in its external face between the shoulder and the end of said projecting portion, the body also having means for supporting an electrical appliance, a globe supported by said projecting portion, a guard for the globe including a member mounted on the external 120 face of said projecting portion and coacting with said shoulder, and a locking member carried by the first-mentioned member and movable relatively thereto into and out of the groove, substantially as and for the purpose specified.

8. The combination of an electrical fitting comprising a hollow body for receiving electric wires, and a projecting portion formed with a groove in its external face, the body 130

also having means for supporting an electrical appliance, a globe supported by said projecting portion, a guard for the globe including a member mounted on the external 5 face of said projecting portion, and a locking member carried by the first-mentioned member and having one end movable relatively thereto into and out of the groove, said members being provided with holes, 10 and the hole of the locking member being arranged to come into alignment with the hole of the first-mentioned member when said end of the locking member is in the

groove, and the aligned holes being adapted to receive additional locking means, substantially as and for the purpose set forth. 15

In testimony whereof, we have hereunto signed our names in the presence of two attesting witnesses, at Syracuse, in the county of Onondaga, in the State of New York, this 20 19th day of January, 1910.
